GUIDE BLADE DEVICE FOR ELASTIC FLUID MACHINES

Filed March 19, 1931

Fig. 1.

UNITED STATES PATENT OFFICE

OSCAR ANTON WIBERG, OF FINSPOONG, SWEDEN

GUIDE BLADE DEVICE FOR ELASTIC FLUID MACHINES

Application filed March 19, 1931, Serial No. 523,907, and in Sweden March 31, 1930.

This invention relates to guide blade devices, and more particularly to such devices which are adapted to be used in connection with radial flow elastic-fluid turbines having one or more expansion stages for axial admission. It is to be noted, however, that the invention is not restricted to such turbines but may be applied to other elastic-fluid machines, as, for instance, compressors.

The object of this invention is to enable a simple mounting and dismantling of the guide blade device, a reliable supporting thereof, and a relief of the device from the load due to pipe lines depending therefrom which may cause deformations and, on the whole, to reduce the necessary pipe lines to a minimum.

A feature of the invention involves the provision on the guide blade device of one or more supporting legs which are arranged so as to permit placing of the guide blade device on suitable parts of the stationary casing of the respective machine or on stays or similar parts rigidly connected to the casing in order that the guide blade device may be wholly or partially supported by said legs.

In the accompanying drawing, one embodiment of the invention is illustrated as applied to a radial flow turbine having blades and discs rotating in opposite directions and having further one axial flow expansion stage at each side.

With reference to the drawing, Fig. 1 is a diagrammatical cross section of the turbine housing and the guide blade device for the axial flow expansion stages. Figs. 2a, 2b and 2c show vertical longitudinal sections of part of the turbine housing. Moreover, Fig. 2a is a section taken on line 2a—2a of Fig. 1 of part of the blade system, whereas Fig. 2b shows the discharging pipe line leading from the guide blade device, partly in section taken on line 2b—2b of Fig. 1. Fig. 2c is a vertical longitudinal view partly in section, taken on line 2c—2c of Fig. 1.

The turbine housing shown in the drawing comprises one upper member 1 and one lower member 2. The lower member rests upon a connecting piece 3 serving as steam

outlet of the turbine which leads to a condenser, not shown. The lower member 2 of the turbine housing is strengthened by transversely extending stays 4 which are formed as brackets 5 to support the casing of the 55 guide blade device. Said casing likewise comprises one upper member 6 and one lower member 7. The casing 6, 7 contains two or more rows of guide blades 8, though two such rows only are shown in the drawing, each of 60 which belongs to an individual rotary wheel 9 for axial admission of the driving fluid. Said rotary wheels 9 are situated on opposite sides of a space 11 surrounding the radial flow system 10 of the turbine which receives the driving fluid escaping from the 65 blade system 10, and from which space said driving fluid will be distributed by the guide blade rings 8, 8 to opposite sides to act upon the two axial flow wheels 9, 9. 70

Resting on said brackets 5, 5 is the lower member 7 of the guide blade casing, said casing having to this end supporting legs 12, 12. In the design illustrated in the drawing, said supporting legs are formed as pipes having 75 base flanges corresponding to the brackets 5, the interior of said legs communicating at the top with the interior of the cover 6, 7 and at the bottom with holes 13 formed in the stays 4. Connected to the lower end of said 80 holes 13 are pipes 14 bolted to flanges of the stays 4 which extend to the outside either through the wall of the connecting piece 3, as shown, or through the lower member of the turbine housing. By way of the connections 12, 13, 14 driving fluid may be discharged from the space 11 between the guide 85 blade rings 8, 8.

Due to the arrangement of the guide blade casing and the discharging pipes, as above 90 described, the lower member 7 of the guide blade casing and said pipes may be packed and adjusted once for all and need not be displaced at every inspection.

The upper member 6 of the guide blade 95 casing is shown as guided by a radial pin 15 in well-known way.

In expansions and contractions due to variations of temperature the turbine housing and the guide blade device will go together, 100

mutual breaking stresses being thus avoided.

What I claim is:—

1. In an elastic-fluid turbine for axial admission, the combination with the stationary housing and rotary system of the turbine of stays in said housing, separate channels in said stays, a guide blade device for said rotary system, a casing for said guide blade device including an annular mantle, and hollow supporting legs projecting laterally from said mantle which communicate with the interior of said device through holes in said mantle and are so positioned as to allow supporting of the device by said stays with the legs in communication with the channels of the stays and with the axis of the guide blade device parallel or substantially parallel to the supporting plane of said stays.

2. In an elastic-fluid turbine for radial admission, the combination of one or more expansion stages for axial admission, a stationary housing for said turbine, a guide blade device for said expansion stages, a casing for said device comprising one upper and one lower member, supporting legs on said lower member formed as discharge pipes laterally projecting from said casing, stays in said turbine housing, channels in said stays, said legs being so positioned as to permit supporting of said lower member by said stays with the legs in communication with said channels, and means to guide said upper member with relation to said stationary housing with said member resting on the lower member of the casing of the guide blade device.

3. In an elastic-fluid turbine for radial admission, the combination of one or more expansion stages for axial admission, a stationary housing for the turbine comprising one upper and one lower member, stays in said lower member, channels through said stays extending from the upper to the lower side thereof, a guide blade device for said expansion stages, a casing for said device comprising one upper and one lower member, supporting legs projecting laterally from said lower member which are formed as discharge pipes, said legs being so positioned as to permit supporting of said casing by said stays with the hollow legs in communication with the channels of the stays and with the axis of the guide blade device extending parallel or substantially parallel to the supporting plane of said stays, means to guide the upper member of the casing with relation to the upper member of the housing with these members resting on their respective lower members, and pipes connected to the channels of the stays at the lower surface of said stays.

4. In an elastic-fluid machine, the combination of a housing, stationary members in said housing having plane supporting surfaces, a guide blade device and a casing therefor comprising one upper and one lower sec-

tion provided in said housing, and hollow supporting legs laterally projecting from the lower section of said casing so as to permit placing of the casing on said surfaces, said hollow legs communicating with the interior of the casing and being open at their free ends in order to permit the discharge of driving fluid through the legs.

In testimony whereof I have signed my name.

OSCAR ANTON WIBERG.
